United States Patent Office.

CHARLES B. BRISTOL, OF NEW HAVEN, CONNECTICUT.

Letters Patent No. 96,877, dated November 16, 1869.

IMPROVEMENT IN WASHING-MACHINES.

The Schedule referred to in these Letters Patent and making part of the same.

To all whom it may concern:

Be it known that I, CHARLES B. BRISTOL, of the city and county of New Haven, in the State of Connecticut, have invented a new and useful Improvement in Washing-Machines; and I do hereby declare that the following is a full, clear, and exact description of the construction, character, and operation of the same, reference being had to the accompanying drawings, which make part of this specification, in which—

Figure 1 is a perspective view of the whole apparatus, showing the two rollers, posts, bar, &c.

Figure 2 is a section of the same, cut vertically through the centre in the longitudinal direction of the rollers.

My improvement consists in the use of two rollers, beaded or fluted transversely, so as to form transversely corrugated surfaces, so arranged that the most prominent portions or beads of one will work in the most depressed portions or grooves of the other, so as to produce both a pressing and a rubbing-operation, as the clothes are alternately drawn up from and lowered down into the water, on either side, by revolving the crank, alternately, in the opposite directions, according to the length of the article to be washed, while the journals of the rollers rest in slots, and the upper roller is pressed down by springs, so as to press the clothes sufficiently, and yet yield readily, to prevent damage to buttons, or any other enlargement or variation in thickness, and in the use of a bar, faced with a strip or plate of India rubber, with its upper edge undulated or serrated, to fit the surface of the lower roller, to prevent strings or small strips of cloth from getting wound around it.

I make the frame of the working-apparatus of two posts, A and B, and a cross-bar, as indicated in section at *a* and *b*, fig. 2, and I secure this bar to the posts by pins, or any other suitable means, and on one of the vertical sides of this bar *a* *b*, I nail, or otherwise secure, a strip or plate of India rubber, as represented at C, figs. 1 and 2, with its upper edge undulated or serrated, as represented at *c*, figs. 1 and 2, to suit the surface of the lower roller, which I place so near to the roller D, as to prevent any string, strap, or narrow strip of cloth from passing round the roller D, so as to entangle or interrupt the work or operation of washing.

I make the posts A and B with a slot in each, as represented at *d* and *e*, from the top to a point sufficiently low, or far enough down, to serve as bearings for the journals of the lower roller D, and I bore or make a round hole in communication with each slot, to receive a suitable spiral spring, as represented at *k*

and *l*, fig. 2, and on the tops of these posts I fit caps, as represented at *f* and *g*, and secure them by screws, as represented at *h* and *i*, figs. 1 and 2, so that the caps may be swung round, to cover or uncover the slots, for the purpose of inserting or removing the journals and springs, whenever it is necessary in using the machine.

I make the rollers D and E with transverse beads and grooves, and so arrange them that the most prominent portions or beads on one roller will work in the most depressed portions of the other, so that if the upper roller E is revolved, the friction of the beads and grooves will cause the lower roller *d* to revolve in the opposite direction, so as to feed any article through in either direction.

I fit the frame into any common wash-tub, as represented in figs. 1 and 2, and turn off the caps *f* and *g*.

Having made the several parts as before described, I drop the roller D into its position, with its journals in the grooves *d* and *e*, where it comes nearly in contact with the serrated edge *c*, of the rubber plate C, on the bar *a* *b*, but so that it may be revolved freely.

I then drop the journals of the upper roller E into the same slots *d* and *e*, and allow it to fall down till its transverse beads or prominent circles fall into the transverse grooves in the lower roller D.

I then drop in the circular pieces of leather, to support the lower ends of the springs *k* and *l*, as represented at *m* and *n*, fig. 2, drop in the springs *k* and *l*, press them down sufficiently, and turn the caps *f* and *g* over the slots *d* and *e*, when the machine will be ready for use.

To use this machine, I put a sufficient quantity of water into the tub F, and put in the clothes, applying soap, &c., at discretion, pass one end or corner of an article to be washed between the rollers D and E, and revolve the roller E, by means of the crank G, until the article has passed nearly through, and then turn the crank in the opposite direction, and so on, alternately, till the article is fully washed.

The advantages of my improvement consist in, that it can be made at far less expense than any other efficient washing-machine, and in that its simplicity precludes all apprehension of liability to get out of repair, and in that the bar and serrated India-rubber plate renders it perfectly secure against strings, and other small parts of articles being washed, getting entangled, torn off, &c., by accidentally getting wound around the lower roller, and in that the transverse beads and grooves, working with

each other, will afford all of the advantages of both pressing and rubbing, with the least strain on the clothes or articles being washed.

What I claim as my invention, and desire to secure by Letters Patent, is—

1. The combination of the two rollers D and E, with the slotted posts A and B, the springs *k* and *l*, and caps *f* and *g*, when constructed, arranged, and fitted for use, as herein described and set forth.

2. The combination of the lower roller D, with the bar *a b*, while sustaining its India-rubber plate C, when they are constructed and arranged as herein described and set forth.

CHAS. B. BRISTOL.
